(57) CLAIM

The ornamental design for a charger for nerve stimulator as shown and described.

DESCRIPTION

FIG. 1 is a top front perspective view of a charger for nerve stimulator, showing our new design;

FIG. 2 is a top rear perspective view of the charger for nerve stimulator of FIG. 1;

FIG. 3 is a front elevation view of the charger for nerve stimulator of FIG. 1;

FIG. 4 is a rear elevation view of the charger for nerve stimulator of FIG. 1;

FIG. 5 is a right elevation view of the charger for nerve stimulator of FIG. 1;

FIG. 6 is a left elevation view of the charger for nerve stimulator of FIG. 1;

FIG. 7 is a top plan view of the charger for nerve stimulator of FIG. 1; and,

FIG. 8 is a bottom plan view of the charger for nerve stimulator of FIG. 1.

The broken lines in the drawings illustrate portions of the article that form no part of the claimed design.

1 Claim, 6 Drawing Sheets
